Theodore Cochen

UNITED STATES PATENT OFFICE.

THEODORE COCHEN, OF WILLIAMSBURG, NEW YORK.

IMPROVED BOTTLE-FILLER.

Specification forming part of Letters Patent No. 55,242, dated June 5, 1866.

To all whom it may concern:

Be it known that I, THEODORE COCHEN, of Williamsburg, Kings county, and State of New York, have invented a new and useful Automatic Bottle-Filler; and I do hereby declare that the following is a full, clear, and exact description of the construction and operation of the same, reference being had to the accompanying drawings, making a part of this specification, in which—

Figure 1 is a top view of my invention; Fig. 2, a side elevation; Fig. 3 a, longitudinal section; and Fig. 4 a view of the siphon detached from the reservoir.

This invention relates to a novel device for filling bottles, demijohns, kegs, &c., with fluid matter to any desired height within the said vessels, but is more especially applicable to the filling of bottles with perfumery, medicine, and other fluid preparations made by drugists and others; and it consists of a reservoir or vat containing a supply-pipe with a plug-valve and float, and a siphon with a valve on its outer end actuated by a spiral spring and the lip of the bottle to be filled, so that the attendant merely places the empty bottle to be filled on the outer end of the siphon, and in doing so opens the siphon-valve, permitting the fluid to flow from the reservoir into the bottle, and when the fluid rises to the desired height within the bottle (which is determined by the float attached to the valve in the reservoir) the fluid will cease to run until the introduction of another empty bottle on the siphon, when the same operation will be performed, and so on for any desired number.

Having described the nature of my invention, I will now describe its construction and mode of operation.

In the drawings, A represents the reservoir which contains the fluid with which the empty bottles are to be filled; B, the supply pipe, with valve-chamber C; D, the supply-pipe valve; E, the valve-stem guide; F, the valve-stem, with screw f, for reception of the swivel nut I; G, the float, with bearing H, which sustains the swivel screw-nut I for adjusting the height of the float on the valve-stem in relation to the quantity of fluid with which the bottles are to be filled.

K is the siphon, attached to the reservoir by a tubular hinge-fastening, L; M, the cock through

which the air in the siphon is drawn out preparatory to the fluid being forced into the siphon by the pressure of the atmosphere.

N is the shorter leg, placed in the fluid in the reservoir, while O is the longer leg, carrying the valve. This valve consists of a circular aperture, P, near to the lower end of the leg O of the siphon and a tube or sheath, R, which slides freely over the aperture and on the said leg. The leg O has also, near its lower end, a flange, S, connected to the said leg by a screw, t, the object of the flange S being to sustain a packing-ring, u, for reception of the tube R, so that as the tube R is (by means of the spring V) pressed down upon the packing the said tube will not only close the aperture P, but make a water-tight joint with the packing-ring during the interval of removing the filled bottle from the stand W and placing an empty one thereon, and thus the charge is retained in the siphon in the meantime.

The operation of my invention is as follows: The fluid being let on will pass down the supply-pipe B, through the valve-chamber C, and into the reservoir A, ascending in the reservoir until the fluid strikes the float G, thereby closing the plug-valve D. The float being already adjusted (by means of the valve-stem F and swivel-nut I) to the desired height of the fluid in the bottle to be filled, and the shorter leg of the siphon immersed in the fluid, I next draw the air from the siphon through the cock M, and close the cock again, and I now introduce the bottle to be filled on the valve end of the siphon, and in doing so press the neck of the bottle against the flange r of the valve and the base of the vessel resting on the stand W, when it is plain to be seen the siphon-valve will be opened and the bottle filled to the desired height, and as the fluid is drawn off from the reservoir the float will drop and the supply-valve open enough to supply the place of that drawn off, and as the bottle is removed the spring V will press the sheath R on its seat, and the siphon-valve will be closed again, and retain its charge for the next bottle without aid from the attendant.

I would here remark that any desired number of siphons may be used without alteration or addition to my device except enlarging the reservoir.

Having described my invention, what I claim, and desire to secure by Letters Patent, is—

1. Placing a valve at the discharging end of the siphon and operating the same by an automatic movement, said valve consisting of the aperture P, the packing-ring u, the sheath R r, and spring V, or their equivalents, substantially as set forth.

2. The peculiar arrangement of the parts which produce a uniformity of supply and dis-

charge—viz., the valve D, valve-stem F, nut I, and float G, when in combination with the reservoir and siphon, substantially as and for the purposes set forth and described.

In testimony whereof I have hereunto set my signature.

THEODORE COCHEN.
